UNITED STATES PATENT OFFICE

WALTER L. MCRAE AND FREDERICK R. COOKE, OF EUCLID VILLAGE, OHIO; SAID COOKE
ASSIGNOR TO FRANK F. KREGENOW, OF CLEVELAND, OHIO

DEVICE FOR VOLATILIZING OR BURNING INCENSE, MEDICAMENTS, AND THE LIKE

Application filed September 23, 1929. Serial No. 384,509.

This invention relates to devices for volatilizing or burning incense, medicinal substances, such as asthmatic inhalants, and other materials adaptable to usage in similar manner; and it is among the objects of the invention to provide a construction which is convenient and readily adaptable to various conditions of usage. Another object is the provision of a heating element which is efficient and compact. A further object is the provision of a controlling means for the heating element, rendering the same automatic in usage. Other objects and advantages will appear as the description proceeds.

To the accomplishment of the foregoing and related ends, the invention, then, consists of the features hereinafter fully described, and particularly pointed out in the claims, the following description and the annexed drawings setting forth in detail certain structure embodying the invention, such being illustrative however of but one of the various ways in which the principle of the invention may be employed.

25 In said annexed drawings:

Fig. 1 is an isometric view of an embodiment of the invention; Fig. 2 is a vertical section thereof, on slightly larger scale; Fig. 3 is a similar fragmentary section, showing the open or charging position of the device; Fig. 4 is an inverse plan view showing the underneath construction of the top of the device; Fig. 5 is a plan view of a detail; and Fig. 6 is a wiring diagram.

Referring more particularly to the drawings, there is shown a casing 2, which may be of any convenient form and size, and which advantageously carries electric contact elements adaptable to ready attachment to a suitable line connection. Such contacts may be of type as desired, prong-receiving or prong-projecting. Preferably, the contacts may take the form of prongs 3 analogous to the standardized plug prongs and such construction is then capable of being directly inserted into a portable plug connection or where a convenient outlet is available in the wall, the prongs 3 may be directly plugged therein, thus serving not only to provide the electric contact but to support the device as

well. The prongs 3 are mounted on suitable insulation blocks 4 secured to the casing, and binding posts or screws 5 afford means for attaching the interior connecting wires.

Mounted within the casing, and preferably also within a refractory housing or tube 6 is a heating element 7. Such heating element may advantageously be of the resistance type, comprising a coil of resistance wire capable of enduring the necessary temperature conditions, and desirably in the form of a grating or spiral or any convenient shape such that material charged thereonto may be supported while being consumed. The refractory tube 6 may be supported in any convenient manner, for instance by a bracket 8 extending from the wall of the casing. Underneath, a slide or small tray 9, with handle 10, may be arranged on runways of desired extent, such that any ash dropping down from the heating or incinerating element may collect for convenient removal.

Preferably, the top of the casing is provided with a closure capable of easy manipulation for charging. In the form illustrated, this comprises a door or lid 11 with openings 12. Air access openings 13 are also provided in the lower part of the casing, for instance in the slide 9. A spring 8 may be applied such as to normally maintain the lid in closed position.

As a current control we may employ a switch of any suitable form, mounted on the casing or separate, so as to enable the operator to apply the current to the heating element as and when required. Instead of such hand-operated switch, where desired the charging-closure or lid may also be employed to operate the switch to connect the heating element in circuit. As one advantageous arrangement for this, the lid being pivotally mounted or hinged as at 14 may have an extension 15 projecting down therebelow, and such extension may carry a contact arm 16 which may be in circuit by a wire connection 17 from the binding post 5. Mounted on the under side of the top of the casing is a stationary contact 18 having a resilient finger-projection in the path of the movable contact arm 16 when the latter is carried forwardly

by raising the lid, the alignment being such that the end 19 of the contact arm 16 will engage the stationary arm 18 when in the open or charging position. If desired, a post 20, conveniently in the form of an adjustable screw, may be interposed at a point between contacts 18 and 19, such that the contact 19 on swinging forwardly may just strike against more or less of the post 20 and with the yielding of the slightly resilient arm 16 in the further movement of the lid, be slightly retarded until it slips past the post 20 with a snap and engages the contact 18. Reversely, as the lid is closed, the post 20 again serves to retard and hold the contact 19 against stationary contact 18 until the lid has been turned down further than would otherwise have been the case. With such adjustment, the timing of the contact may be set closely within such limits as may be desired. The contact 18 may be mounted on an insulating block in any desired manner.

Under most usages, the heating element 7 need not exceed a few turns of wire, and if the current supply is of a voltage to exceed the requirements for such, a ballasting resistance, for instance in the form of a winding 21 may be conveniently disposed on the refractory tube 6, such resistance being in series with the heating coil 7 and serving to cut down the current to the heater requirements. Of course, where large capacity installations are involved, such ballasting may be omitted. With a connecting wire 22 on the binding post of the prong, the circuit through the ballast and heating coil is completed.

In use, a mass of the material to be volatilized or burned is charged into the device by opening the lid 11. The material drops upon the heating element 7, which has been quickly raised to red heat by the flow of the current, the contact 19 having been swung by the lid into engagement with the stationary contact 18, allowing the current to flow from the binding post of one of the prongs 3 to the connecting wire 17 and the contacts 19, 18, to the heating element, and ballast resistance if such be employed, the circuit being completed by wire 22 to the other binding post and prong. With a suitably proportioned heater element, the time interval occasioned by the movement of the lid 11 and the incidental lag provided by the switching mechanism in conjunction therewith, suffices to heat the element to a temperature requisite to consume the material charged. The current being cut off by the breaking of the contact on closure of the lid, only such current drain as is actually required has to be reckoned with, and the device is correspondingly exceedingly economical.

It will thus be seen that a device readily portable and convenient of usage under various circumstances encountered, is had, and

whether employed for perfuming and deodorizing, or for asthmatic inhalants, or insect repellent usage, the device may be inserted into any available plug, either portable or in the nature of a fixed convenience outlet. The current requirements, as noted, can be held at the minimum requisite to consume the material operated upon, and thus the device is inexpensive in maintenance.

Other modes of applying the principle of the invention may be employed, change being made as regards the details described, provided the means stated in any of the following claims, or the equivalent of such, be employed.

We therefore particularly point out and distinctly claim as our invention:

1. In a device of the character described, a casing, an electric heating element and material-receiving member therein, and contacts carried by the casing for co-acting with a wall fixture to support said casing and also provide the service connection for the circuit of said heating element.

2. In a device of the character described, a casing, an electric heating element, a refractory housing thereabout and presenting an air-inlet opening below, a closure over said heating element, and a switch actuated by movement of said closure.

3. In a device of the character described, a casing, an electric heating element, a closure affording access to said heating element, a switch controlling the current to said heating element, and regulable means for retarding the operation of said switch.

4. In a device of the character described, a casing, an electric heating element, a closure affording access to said element, a contact carried by said closure and adapted to engage a fixed contact in circuit with said heating element, means for retarding the engagement and disengagement of the movable contact with the fixed contact and means for regulating the amount of retardation.

5. In a device of the character described, a casing, an electric heating element in the form of a grating, a closure affording access to said heating element, prongs projecting from said casing, and an automatic switch actuated by said closure for connecting the heating element in circuit with the prongs.

6. In a device of the character described, a casing, an electric heating element, a refractory housing thereabout, and a ballasting resistance on said housing and in circuit with said heating element.

7. In a device of the character described, a casing, an electric heating element, a refractory housing thereabout, a lid affording access to said heating element, prongs projecting from said casing, a contact movable with said lid and adapted to engage a fixed contact in circuit with said heating element,

and a ballasting resistance on said refractory housing.

8. In a device of the character described, a casing, an electric heating element in the form of a spiral grating, a refractory tube thereabout, a charging lid affording access to said heating element, a removable ash tray therebeneath, plug-in prongs projecting from said casing, a contact movable with said lid to engage a fixed contact, and a ballasting resistance in series with said heating element.

9. In a device of the character described, a casing, a heating element in the form of a spiral grating, a refractory tube thereabout, a charging lid affording access to said heating element, a removable ash tray therebeneath, plug-in prongs projecting from the back of said casing, a contact arm movable with said lid and adapted to engage a fixed contact in series with said heating element, an adjustable post in the path of said movable contact adapted to retard the engagement and disengagement thereof with the fixed contact, and a ballasting resistance on said refractory tube in series with said heating element and said contacts and prongs.

Signed by us this 21st day of September, 1929.

WALTER L. McRAE.
FREDERICK R. COOKE.
